SERVING SPOON OR SIMILAR ARTICLE

Samuel M. Highberger, Oak Park, Mich.

Application August 16, 1955, Serial No. 37,498

Term of patent 14 years

(Cl. D54—12)

Fig. 1 is a top elevational view of a serving spoon embodying my new design;

Fig. 2 is an elevational view taken on the line 2—2 of Fig. 1;

Fig. 3 is a bottom elevational view of the serving spoon disclosed in Fig. 1; and

Fig. 4 is an elevational view taken on the line 4—4 of Fig. 3.

I claim:

The ornamental design for a serving spoon or similar article, substantially as shown.
